F. LAMATSCH

FOLDING BLADE ADJUSTMENT MECHANISM

Filed Nov. 1, 1926

FIG. 1.

-FIG. 2.-

Patented Aug. 23, 1927.

1,639,948

UNITED STATES PATENT OFFICE.

FREDERICK LAMATSCH, OF GRANTWOOD, NEW JERSEY, ASSIGNOR TO R. HOE & CO., INC., OF NEW YORK, N. Y., A CORPORATION OF NEW YORK.

FOLDING-BLADE-ADJUSTMENT MECHANISM.

Application filed November 1, 1926. Serial No. 145,585.

The invention relates to mechanism used in connection with printing presses for folding the printed sheets before final delivery from the press, and it relates particularly 5 to the folding or tucker blade and mechanism for adjusting the same.

The objects and advantages of the invention will be in part set forth in the following specification and in part will be obvious 10 therefrom without being specially pointed out, the same being realized and attained by means of the instrumentalities and combinations pointed out in the claims hereof.

The invention consists in the novel construction, arrangement and combination of 15 various elements and parts, as set forth in the claims hereof, one embodiment of the same being illustrated in the accompanying drawings and described in the specification.

20 In the accompanying drawings,

Fig. 1 is a fragmentary view of a printing press, showing in transverse vertical section a portion of the paper folding mechanism, and

25 Fig. 2 is a view at right angles to the same, showing parts of the frame or supporting members in section.

In printing presses of the kind to which this invention relates, there are supported 30 in a suitable framework cutting cylinders, which are designated in the accompanying drawings 11 and 12 respectively, which are mounted as usual on shafts 17 and 18. These cutting cylinders are provided with the usual 35 cutting devices, indicated at 13, which operate to sever a web of paper 14. The cylinders are also provided with the usual paper-engaging pins 15 and 16 and the operating devices therefor, and within the cylinder 12 40 are also provided a plurality of rotary tucking blades 19, located at suitably spaced points, mounted upon shafts 20 journaled in suitable bearings. These shafts bear spur gears 21 which engage with an internally 45 geared rack 22, adjustably mounted on the frame of the machine so as to normally remain stationary with regard to the cylinder 12, but to be capable of a slight rotatorial adjustment for the purpose and by the 50 means now to be described.

Secured to the upper portion of the rack 22 is a bracket 30. Secured to the outer frame surrounding the rack 22 is a bracket 31. Operatively connecting the brackets 30 and 31 is a screw 32, by the rotation of

which these brackets may be separated or brought nearer together and consequently the rack 22 rotated in its bearings. Bolts and nuts 33 are provided, which may be released to allow the rack 22 to be rotated, and tightened again after the same has been adjusted into the desired position.

Beneath the roller 12 are the usual folding-off rollers 35. In order to provide for the passage between these rollers of a larger 65 or smaller number of sheets of paper, the left hand roller is made adjustable by the screw 36 acting in the bearing 37, which upon being rotated shifts laterally the bearing 38 of the left hand member of the pair 70 of rollers 35.

The operation of my invention is as follows: Referring more particularly to Fig. 1 of the drawings, the web 14 is shown leading down from the former, which is located 75 above but not shown in the drawings. In the drawings the web is shown as having been carried down past the cutting knife and past the tucking-in blade 19, in order to illustrate the operation of the same, but it 80 will be understood that at the beginning of the operation the leading edge of the web is brought down and introduced between the rollers 11 and 12 and engaged by the pins 85 15. The leading edge of the web is then drawn around the cylinder 11 in the direction of the arrow and when it has made a complete turn the knife mechanism 13 operates to sever the portion which surrounds the roller 11 from the remainder, the pins 15 90 are released, and the pins 16 of the roller 12 operate to engage with not only the leading edge of the paper which has been carried around the cylinder 11 but also the leading edge of the following portion of the web 95 14. There will then be two superimposed or associated sheets held by the pins 16, and these associated sheets are carried on around the large cylinder until the tucking blade 19 100 pushes them in between the folding-off rollers 35 by which they are given the final fold and are passed on to the delivery belts.

When the paper is folded off between the rollers 35, they must of course be placed close enough together to grasp the paper 105 and draw it away from the cylinder 12. When a relatively small amount of paper is being folded, these rollers will necessarily be close together, but when a large number 110 of sheets of paper associated are being fold-

ed, the folding-off rollers 35 must be adjusted considerably further apart, which is done by adjusting the screw 36 above described. It is obvious, however, that the path of the tucking blade 19 should pass exactly in the middle of the space between the two rollers, and hence when a large volume of paper is being folded and the folding-off rollers are separated by a larger space than is otherwise the case, the position of this blade 19 must be further to the left than when a thin paper is being folded, and one of the principal objects of my invention is to provide means whereby this necessary adjustment can be made.

As the tucking blades are carried on shafts having bearings in the cylinder 12, which shafts are carried around as the cylinder rotates, and as these shafts bear gears which mesh with a relatively stationary internal gear 22, it is obvious that the position of the tucking blades with regard to the folding-off rollers 35 depends upon the adjustment of the internal gear 22 relative to the rotating cylinder 12. When it is desired therefore to cause the downward or tucking-in position of the blade 19 to take place at a different place, this is easily effected, in an apparatus constructed according to my invention, by slightly adjusting rotatorily the internal rack 22. For instance, if a large number of sheets are to be folded, the left hand folding-off roller 35 is moved slightly to the left by the screw 36, thus increasing the space between the rolls 35. The nuts 33 are then loosened, and the annular rack 22 rotated slightly but sufficiently for the purpose in a clockwise direction by means of the adjusting screw 32, until the parts are placed in such relative position that the tucking blade 19 stands in a straight radial direction from the centre of the shaft 18 when it is half way between the folding off rollers 35, whereupon the nuts on the adjusting screw 32 are tightened, and the nuts 33 which secure the annular rack 22 are also screwed down tight, and the operation of the machine proceeds as before, the only difference being that the tucking-in operation of the blade 19 between the folding-off rollers 35 occurs at a slightly further advanced position of the roller 12 than is the case when but a few sheets of paper are being folded and the rollers 35 are consequently very near together.

Having thus described my invention, what I claim as new and desire to secure by Letters Patent is as follows:

1. In folding mechanism for printing presses and the like, the combination with a suitable supporting frame and folding-off rollers journaled therein, one of said rollers being adjustable toward and away from the

other; of a cylinder journaled in said frame adapted to convey paper to be folded to said folding-off rollers, a rotary tucking blade mounted in said last-named cylinder and adapted to tuck paper in between said folding-off rollers, and means for rotating said tucking blade, comprising an internal gear adjustably secured to said frame, a spur gear adapted to engage with said internal gear and operatively connected to said tucking blade, and means adapted to adjust said internal gear rotatorially with relation to said folding-off rollers.

2. In folding mechanism for printing presses and the like, the combination with a suitable supporting frame and folding-off rollers journaled therein, one of said rollers being adjustable toward and away from the other; of a cylinder journaled in said frame adapted to convey paper to be folded to said folding-off rollers, a rotary tucking blade mounted in said last-named cylinder and adapted to tuck paper in between said folding-off rollers, and means for rotating said blade, comprising an internal gear rotatably secured to said frame, means for adjusting the same with relation to said frame, means for securing said internal gear fast on said frame when adjusted at a predetermined position, and a spur gear adapted to engage with said internal gear and operatively connected to said tucking blade.

3. In folding mechanism for printing presses and the like, the combination with a suitable supporting frame and folding-off rollers journaled therein, one of said rollers being adjustable toward and away from the other; of a cylinder journaled in said frame adapted to convey paper to be folded to said folding-off rollers, a rotary tucking blade mounted in said last-named cylinder and adapted to tuck paper in between said folding-off rollers, and means for rotating said blade, comprising an internal gear rotatably secured to said frame, means for adjusting the same with relation to said frame, means for securing said internal gear fast on said frame when adjusted at a predetermined position, and a spur gear adapted to engage with said internal gear and operatively connected to said tucking blade: said internal gear adjusting means comprising a bracket on said internal gear and movable with the same, a second bracket independent of said internal gear and stationary, and an adjusting screw passing through said brackets and adapted when rotated to draw said brackets nearer together or impel same further apart.

In witness whereof I have hereunto signed my name this 26th day of October, 1926.

FREDERICK LAMATSCH.
